PRESS CONTROL MECHANISM

Angus F. Hanney, Norwood, Ohio, assignor to The American Laundry Machinery Company, Norwood, Ohio, a corporation of Ohio

Application August 29, 1935, Serial No. 38,400

10 Claims. (Cl. 38—25)

This invention relates to a pressing machine and particularly to a control mechanism therefor.

My invention provides a pressing machine having a pair of coacting pressing members and motor means for causing preliminary and final closing movement of the pressing members, together with novel means for actuating the final closing movement by utilization of air compressed by the motor means during the preliminary closing movement.

My invention also provides a pressing machine in which one member is moved to a position adjacent the other by mechanism which when so positioned resists pressure against the said one member, together with motor means for moving the other member into final pressure engagement with its coacting member. In such a machine I provide a novel controlling device for the motor with a novel operative connection between this mechanism and the mechanism which moves the first named pressing member.

My invention provides a pressing machine of the type utilized in laundry and garment work with a safe means for moving the pressing members to position closely adjacent each other and a novel means for initiating the final closing movement.

Another feature of my invention is the provision of a novel valve operating device.

Other novel features of my invention will appear from the accompanying specification taken in connection with the drawing and the essential features will be summarized in the claims.

In the drawing, Fig. 1 is an end elevation of a pressing machine embodying my invention part of the mechanism being shown in section and the control devices being shown somewhat diagrammatically; Fig. 2 is an enlarged sectional view through a portion of the valve mechanism of Fig. 1; while Fig. 3 is a view of a portion of the mechanism of Figs. 1 and 2 taken in approximately the position of the line 3—3 of Fig. 1.

I have shown my improved control mechanism as applied to pressing machines which are commonly found in laundries or garment pressing establishments, although it will be understood that certain features of my invention are applicable to other types of machines. In the present embodiment, on a frame 10 is pivotally mounted a head lever 11 which carries at its forward end a pressing head 12 which may be heated in any suitable manner, not shown, if such heating is desirable. Between the rear end 55 of the head lever and the frame is connected a

pair of toggle links 13 and 14 for moving the head into and out of pressing position. A spring 15 biases the links toward broken position which corresponds with the open position of the head. For moving the head to pressing position I provide a motor 16 having a cylinder 16a and a piston 16b whose rod 16c is suitably connected to the toggle links so that upon a power stroke of the motor the links are moved into and preferably beyond straightened position as shown in broken lines in Fig. 1. Movement of the links is limited by engagement of the shoulders 13a and 14a. This broken line position of the links corresponds to the broken line position of the head shown in Fig. 1, which is closely adjacent the bed so that there is no danger of an operator placing her fingers in position between the pressing members. A snubbing device 17 is engaged by the toggle links as they move into strut forming position and this device also serves to give the toggles an initial kick toward broken position when the press opens. It will be noted that with the toggles in the broken line position of Fig. 1 they hold the pressing head in position to resist upward pressure against it which is later exerted by the bed.

For coaction with the pressing head a bed 18 is provided preferably suitably padded and movable vertically in a portion of the press frame during which movement it is guided by suitable pins 19. A pressure pin 20 depends below the bed in a suitable bearing and is engaged by the piston 21b of a motor 21 mounted on the frame and having a cylinder 21a.

Motive fluid is supplied to motor 16 from a suitable source 22 and preferably by a two-hand control device whereby the motive fluid passes through valve casing 23, conduit 24, valve casing 25 and conduit 26 to the cylinder 16a. Casing 23 houses a normally closed inlet valve 23a having a stem 23b which is actuated by manual 23c. Casing 25 houses a normally closed inlet valve 25a and a normally open outlet valve 25b both mounted on a common stem 25c which is actuated by manual 25d. These manuals 23c and 25d are so spaced at the front of the press before the operator as to require the use of one hand on each manual to operate the press and it will be understood by those skilled in the art that both manuals must be opened and held opened until motor 16 has completed the power stroke to move the head from its full line position to its broken line position in Fig. 1.

The power supply for motor 21 includes a control member which is operable only upon sufficient

movement of motor 16 to place the head in its safe position adjacent the bed. In the form shown this includes an air operated device for the control member of motor 21 and air is supplied to this device effectively only after piston 16b has substantially completed its power stroke. In the particular form shown this air for the operation of the control member for motor 21 is compressed behind piston 16b in the cylinder 16a as the piston moves along the cylinder and I desire to claim this novel construction although it will be understood that air might be supplied to the control member for motor 21 by other suitable arrangements.

15 In the construction shown motive fluid for motor 21 is supplied from conduit 22 or other suitable source through conduit 27, valve casing 28 and conduit 29. Valve casing 28 houses a normally closed inlet valve 28a and a normally open outlet valve 28b. Preferably these valves are mounted on separate stem portions, the inlet valve being carried on stem 28c and biased toward closed position by a spring 28d. The outlet valve is carried by stem 28e which lies opposite stem 28c in position to abut the same when stem 28e is pressed inwardly. The device shown for actuating valve stem 28e comprises a servo-motor 30 having a cylinder 30a in which reciprocates a piston 30b whose piston rod 30c is rigidly connected with a device for actuating the valves in casing 28. A spring 30d serves to return the piston 30b to its idle position at the rear or left hand end of the cylinder 30a after a power stroke. Preferably also this spring performs a second function, later described, and to this end one end of the spring is fixed at the point 31 and the other end is secured to the piston 30b at the point 32. The structure connected to the piston rod 30c at its outer or forward end comprises an arm 33 having a portion 33a which is adapted to engage a portion of the valve mechanism in casing 28 in a manner to actuate the valves therein. In the form shown this portion 33a is movable by oscillation of the arm 33 to a position overlying the forward end of valve stem 28e. A handle portion 33b is rigidly connected with arm 33 to rotate the same in a counterclockwise direction. Such rotation because of the rigid connection between arm 33 and piston 30b by means of the rod 30c will load the spring 30d by twisting the same. This loading of the spring biases the arm 33 so that it tends to move in a clockwise direction to position the portion 33a in valve actuating position again the stem 28e. Such clockwise movement of arm 33 is limited by the engagement of the shoulder 33c on the arm with the valve stem 28e. This position of the parts is shown in Fig. 3. When however the arm 33 has been moved outwardly or to the right as shown in Figs. 1 and 2 until the portion 33a is clear of the stem 28e, the loaded spring 30d will oscillate arm 33 to the right until such movement stops because of the engagement of pin 34 with the shoulder 33d on arm 33. A conduit 35 communicates between the rear end of cylinder 16a and the working face of piston 30b so as to conduct air compressed by a power stroke of piston 16b to the servo-motor 30. A small vent 30e is provided in the rear end of cylinder 30a for a purpose later described.

70 It is thought the operation of the pressing machine and its control mechanism will now be clear. With the parts in the full line position of Fig. 1, the operator arranges the lay of the work upon the bed 18 and depresses manuals 23c and

25d. This admits motive fluid to motor 16 which makes a power stroke moving the toggles and the pressing head to the broken line position of Fig. 1. The parts are so arranged that the piston 16b has substantially completed its power stroke before sufficient fluid is compressed in cylinder 16a and delivered through conduit 35 to servo-motor 30 to overcome spring 30d. When this takes place, however, piston 30b makes a power stroke toward the right as seen in Figs. 1 and 2 compressing spring 30d and moving arm 33 to the right until portion 33a clears stem 28e whereupon spring 30d which has been previously loaded by twisting, causes clockwise rotation of arm 33. This places portion 33a over stem 28e. Motive fluid very quickly leaks out the vent 30e sufficiently to permit spring 30d to return piston 30b to the left hand end of its cylinder, carrying with it the arm 33 which thereby moves valve stems 28e and 28c to the left, closing valve 28b and opening valve 28a. This admits motive fluid to motor 21 which makes a power stroke vertically upward which raises bed 18 into engagement with the head member 12. The toggle links are thus held in the strut-forming position shown in broken lines in Fig. 1 as long as motive fluid is supplied to motor 21 and the operator may release manuals 23c and 26d whereupon pressure is evacuated from cylinder 16a through valve 25b although the piston remains at the rearward end of the cylinder. To open the press the operator actuates arm 33b to oscillate the arm 33 in a counterclockwise direction which moves portion 33a away from stem 28e releasing this stem, whereupon spring 30d closes valve 28a and opens valve 28b to exhaust motor 21. Thereupon the bed 18 and piston 21b move downwardly due to the action of gravity on the parts and the device 17 and spring 15 return the pressing head and connected parts to the full line position of Fig. 1 ready for another operation. The movement of arm 33b in a counterclockwise direction to cause press opening twists spring 30d in a manner to reload the same thus placing the parts again in the position of Fig. 3.

What I claim is:

1. In a pressing machine, a pair of coacting relatively movable pressing members, a cylinder and piston motor for causing relative movement between said members and into a preliminary position, said motor being arranged to compress air by a power stroke of its piston, a second motor for causing relative movement between said members and into final pressing position, a control member for said second motor, an air operated device for controlling said control member, and means for supplying to said device sufficient air for operation thereof by movement of said first motor sufficient to cause said relative movement into preliminary pressing position.
2. In a pressing machine, a pair of coacting relatively movable pressing members, motor means operable in two steps for causing relative approach movement between said pressing members, a first step into preliminary position and a second step into final pressing position, control members for said motor means for controlling each of said steps, said motor means being arranged to compress air during said first step, an air operated device for actuating said second step control member, and means for conducting said compressed air to said device, said air compressing arrangement and device being so constructed that air sufficient to operate said device is supplied

thereto by first step operation of said motor means.

3. In a pressing machine, a pair of coacting relatively movable pressing members, motor means operable in two steps for causing relative approach movement between said pressing members, a first step into preliminary position and a second step into final pressing position, control members for said motor means for controlling each of said steps, a device for actuating said second step control member, means for cocking said device, said device being operable when uncocked to actuate said second step control member in fluid supply direction, and means operable by said motor means upon completion of said first step for uncocking said device.

4. In a pressing machine, a pair of coacting pressing members, mechanism for moving one of said members into position adjacent the other, said mechanism being constructed and arranged so that said one member when in said position resists pressure against it, a motor for moving said mechanism to place said one member in said position, control means for said motor, fluid actuated means for moving the pressing surface of said other member against said one member in said adjacent position, control means for said last named means including a fluid supply valve and a device for actuating said valve, said device including a part having a reciprocating and an oscillatory movement, spring means for causing at least one of said movements, means for loading said spring and for holding it loaded, and means for releasing said spring and for causing the other of said movements, said last named means being operable by movement of said motor sufficient to place said one member in said adjacent position.

5. In a pressing machine, a pair of coacting pressing members, mechanism for moving one of said members into position adjacent the other, said mechanism being constructed and arranged so that said one member when in said position resists pressure against it, a motor for moving said mechanism to place said one member in said position, control means for said motor, fluid actuated means for moving the pressing surface of said other member against said one member in said adjacent position, control means for said last named means including a fluid supply valve and a device for actuating said valve, said device including a valve actuating part normally held in non-actuating position, means biasing said part toward actuating position, and means for releasing said part for movement toward actuating position, said last named means being operable by movement of said motor sufficient to place said one member in said adjacent position.

6. In a pressing machine, a pair of coacting pressing members, mechanism for moving one of said members into position adjacent the other, said mechanism being constructed and arranged so that said one member when in said position resists pressure against it, a motor for moving said mechanism to place said one member in said position, control means for said motor, fluid actuated means for moving the pressing surface of said other member against said one member in said adjacent position, control means for said last named means including a fluid supply valve and a device for actuating said valve, said device including a valve actuating part normally held in non-actuating position, means biasing said part toward actuating position, and means for releasing said part for movement toward actuating

position and for causing actuating movement of said part, said last named means being operable by movement of said motor sufficient to place said one member in said adjacent position.

7. In a pressing machine, a pair of coacting pressing members, mechanism for moving one of said members into position adjacent the other, said mechanism being constructed and arranged so that said one member when in said position resists pressure against it, a motor for moving said mechanism to place said one member in said position, control means for said motor, fluid actuated means for moving the pressing surface of said other member against said one member in said adjacent position, control means for said last named means including a fluid supply valve and a device for actuating said valve, said device including a valve actuating part having an oscillating movement into valve actuating position and a reciprocating movement for valve actuation, means for biasing said part toward actuating position, means holding said part in non-actuating position, spring means for causing said reciprocating movement in valve-actuating direction, means for loading said spring means and for releasing said holding means, and an operative connection between said last named means and said motor whereby said last named means is operable by movement of said motor sufficient to place said one member in said adjacent position.

8. In a pressing machine, a pair of coacting pressing members, mechanism for moving one of said members into position adjacent the other, said mechanism being constructed and arranged so that said one member when in said position resists pressure against it, a motor for moving said mechanism to place said one member in said position, control means for said motor, fluid actuated means for moving the pressing surface of said other member against said one member in said adjacent position, control means for said last named means including a fluid supply valve and a device for actuating said valve, said device including a cylinder and piston servomotor having a power stroke in one direction, said piston having a piston rod, an arm rigidly carried by said rod and adapted upon rod oscillation to engage a part of said valve, a spring compressible by said power stroke and adapted to return said piston to idle position after a power stroke, said return stroke of said piston being adapted to move said arm in valve-actuating direction, said spring having one end fixed and the other end secured to said piston, means for rotating said arm and piston to move said arm out of valve engagement and to twist said spring into position adapted to cause return movement of said arm, means holding said arm in said out-of-engagement position and releasable by a power stroke of said piston, and means for supplying motive fluid to said servomotor by operation of said press motor sufficient to place said one member in said adjacent position.

9. In a pressing machine, a pair of coacting pressing members, mechanism for moving one of said members into position adjacent the other, said mechanism being constructed and arranged so that said one member when in said position resists pressure against it, a motor for moving said mechanism to place said one member in said position, control means for said motor, fluid actuated means for moving the pressing surface of said other member against said one member in said adjacent position, control means for said last

named means including a fluid supply valve and a device for actuating said valve, said device being normally in non-actuating position, and means operable by movement of said motor sufficient to place said one member in said adjacent position for placing said device in valve-actuating position.

10. In a pressing machine, a pair of coacting relatively movable pressing members, motor means for causing relative approach and separa-

ting movement between said members, said motor means being arranged to compress air during an initial portion of its press-closing cycle, a control member for said motor means for controlling the latter portion of the press-closing cycle thereof, an air actuated device for operating said control member, and means for conducting said compressed air to said device.

ANGUS F. HANNEY. 10
